DISH FOR CORN ON EAR

Bernard Graham, Pittsburgh, Pa.

Application November 30, 1949, Serial No. 6,344

Term of patent 14 years

(Cl. D44—10)

To all whom it may concern:

Be it known that I, Bernard Graham, a citizen of the United States of America, residing at Pittsburgh, in the county of Allegheny, State of Pennsylvania, have invented a new, original, and ornamental Design for a Dish for Corn on Ear, of which the following is a specification, reference being had to the accompanying drawing forming a part thereof.

Figure 1 is a top plan view of a dish for corn on ear showing my new design; Fig. 2 is a side elevational view; Fig. 3 is a bottom plan view; Fig. 4 is an end elevational view, and Fig. 5 is a sectional view thereof taken on the line V—V of Fig. 2.

I claim:

The ornamental design for a dish for corn on ear, as shown.

BERNARD GRAHAM.
